SHIELDED IGNITION COIL

Carleton S. Marden, Waltham, Mass., assignor to National Products Corporation, Boston, Mass., a corporation of Massachusetts

Application February 2, 1953, Serial No. 334,662

8 Claims. (Cl. 123—148)

This invention relates to electrical connections between high voltage components such as the spark coil and distributor of an internal combustion ignition system, and particularly to electromagnetic shielding of such connections to prevent radio interference generated by the high tension current.

It is common practice, particularly in military vehicles, to shield the cables leading between the high voltage terminals of such components. The recent trend is toward completely shielding the cables and all the components. While it is possible for the manufacturer of the vehicle to assemble the component and cable shields on the production line it is highly desirable to have the component shields and associated shielded cables preassembled in what is known as a harness. In a harness the cables interconnect the shielded attachments intended to be connected to the terminals of the various components and the cable ends are provided with connectors adapted to make electrical contact with the terminals of the components so that the manufacturer may complete the connections without soldering or otherwise assembling the system with the aid of special tools.

Notwithstanding the desirability of such a harness it is difficult to manufacture a shield with the attached connectors in proper position to fit the terminals of the component.

One object of the present invention is to provide a harness including a shield adapted for easy attachment to a high voltage component which is particularly adapted to preassembly, and which has sufficient flexibility in the electrical connection to facilitate attachment of the shield and connector.

A further object is to provide a shielded connection for socket type terminals such as the tubular high tension terminal of a spark coil. Other objects are to provide a shielded connection which is simple and economical in manufacture, particularly adapted to mass production techniques and which generally improves the art.

In one aspect the invention involves a shielded connector for connecting an ignition cable to a high voltage component having a cylindrical casing and a tubular socket terminal member, the shielded connector comprising a tubular metallic hood adapted to telescope over the casing and shield said terminal, a cable entrance into the hood, suitable means for connecting the cable to the aforesaid socket terminal member including an insert fitting in said member, and a resilient sheath gripping the connecting means, the sheath having a sleeve portion adapted to engage the outside of the terminal member and hold the connecting means attached thereto. Preferably the connecting means further includes a clip for attachment to the cable, the clip being formed to telescope over and grip the aforesaid insert. Preferably the insert is a cylindrical plug fitting in the socket terminal member, and the sleeve portion of the sheath is of greater internal diameter than the plug so that it is adapted to expand and engage outside the terminal member.

2

The shielded connector is particularly adapted for assembly in a harness comprising an ignition cable having a metallic shield, the aforesaid cable entrance including grounding means for attaching the end of the shield to the hood short of the end of the cable, and the sheath on the end of the cable being spaced from the cable entrance and loosely supported on the end of the cable.

Preferably the hood has at one end a mouth portion adapted to telescope over and electrically contact the aforesaid tubular casing so that the hood encloses the terminal, hood and casing entirely shielding the component, and the hood includes a detachable closure at the other end thereof and means interengaging the closure and hood externally of the hood to afford unimpeded access to the terminal and cable end when the hood is attached to the casing.

For the purpose of illustration a typical embodiment of the invention is shown in the accompanying drawings in which:

20 Fig. 1 is an exploded isometric view of a shielded connector for a spark coil;

Fig. 2 is a plan view of the shielded connection assembled in a harness, parts being omitted; and

25 Fig. 3 is a side elevation partly in section of the harness assembly.

In the figures the spark coil, which is illustrative of a high voltage component, comprises a metallic casing 1 enclosing the coil proper 5, a metallic cap member 1a attached as a part of the casing 1, an insulating member 2 including a tubular socket 2a, low voltage terminals 3 extending from the insulating member 2 and a cup-shaped female terminal 4 seated within the tubular member 2a and connected by a wire 6 to the coil 5.

The shielded connector includes a tubular hood 11 having a cap 12 and three cable entrances 13 for admitting the cable 14 within the hood. The cable 14 includes a braided shield 16, insulation 17 and a conducting wire 18. The cable entrances 13 are each provided with a nut 19 for clamping the end of the braided shield 16 and grounding the end of the shield to the cable entrance 13. The end of the shielding 16 stops short of the end of the insulation 17 and the conductor 18, these parts of the cable extending through the entrance 13 to within the shield. In the case of the low voltage terminals the conductor 18 may be attached by means of a nut 21.

45 In the case of the high voltage socket 2a the insulation 17 and conductor 18 extend into a sheath of rubber-like material 22. The insulation 17 being gripped by the sheath, and the conductor 18 being electrically connected to a coil spring clip 23 gripped by the sheath 22. The coil spring 23 has a pointed extension 24 adapted to pierce the insulation 17 and make electrical contact with the conductor 18.

55 The sheath 22 fits over the upper end of a metal plug 26 generally of cylindrical shape. The plug is radially slit to form resilient bifurcations 27 designed to fit yieldingly with the female terminal 4 of the spark coil. The tubular plug 26 extends above the tubular socket 2a and may be made in any size to fit the female terminal 4 of various spark coils. Variations in the diameter of the bifurcated portions 27 of the plug do not require any change in the coil clip 23 or sheath 22. This interchangeability of the plug affords a great economy in cost and time in the assembly and attachment of the harness.

60 The sheath 22 is provided with a sleeve portion 25 of greater internal diameter than the plug 26. The sleeve portion may be expanded and telescoped over the outside of the tubular socket 2a. In this position the sheath firmly grips the socket 2a holding the coil clip 23 and plug 26 in firm electrical connection with each other and with the female terminal 4. The sleeve 25 also forms a

waterproof seal around the high voltage terminal socket 2a excluding condensation and other foreign substances which might provide a conductive path for the high tension current to the shielded hood 11, the casing 1 or the low voltage terminals 3. As can be seen with reference to Fig. 3 the sheath 22 is loosely held on the cable insulation 17, that it is not fixed rigidly with relation to the hood 11. Consequently after the hood 11 is telescopingly attached to the casing 1, removal of the cap 12 permits access to the sheath 22 for firm attachment of the sheath to the terminal socket. The threading 10 on the cap and hood is external of the hood so that when the cap is removed there is no obstruction of the terminals 3 and 4.

It can be seen from the foregoing description that the present shielded connection is readily adapted to fit various spark coils or like components, that it is simply assembled in an ignition harness, and provides a reliable electromagnetic shield and a waterproof seal for the high voltage terminal.

It should be understood that the present disclosure is for the purpose of illustration only and that this invention involves all modifications and equivalents which fall within the scope of the appended claims.

I claim:

1. For connecting an ignition cable to a high voltage component having a cylindrical casing and a tubular socket terminal member, a shielded connector comprising a tubular metallic hood adapted to telescope over the casing and shield said terminal, means forming a cable entrance into said hood, means for connecting said cable to said socket terminal member including a removable insert fitting in said member, and an elastic sheath resiliently gripping said means, said sheath having a sleeve portion adapted to engage the outside of said terminal member to hold said connecting means attached thereto and enclose and seal said socket.

2. For connecting an ignition cable to a high voltage component having a cylindrical casing and a tubular socket terminal member, a shielded connector comprising a tubular metallic hood adapted to telescope over the casing and shield said terminal, means forming a cable entrance into said hood, means for connecting said cable to said terminal member including a removable insert fitting in said member, and a clip for attachment to said cable, said clip being formed to telescope over and grip said insert, and an elastic sheath resiliently gripping said clip, said sheath having a sleeve portion adapted to engage the outside of said terminal member to hold said connecting means attached thereto and enclose and seal said socket.

3. For connecting an ignition cable to a high voltage component having a cylindrical casing and a tubular socket terminal member, a shielded connector comprising a tubular metallic hood adapted to telescope over the casing and shield said terminal, means forming a cable entrance into said hood, means for connecting said cable to said terminal member including a removable, cylindrical insert plug fitting in said member and a clip for attachment to said cable, said clip being formed to telescope over and grip said insert, and an elastic sheath resiliently gripping said clip, said sheath having a sleeve portion of greater internal diameter than said plug adapted expandingly to engage the outside of said terminal member to hold said connecting means attached thereto and enclose and seal said socket.

4. A harness for connection to a high voltage component having a cylindrical casing and a tubular socket terminal member, comprising a tubular metallic hood adapted to telescope over the casing and shield said terminal, an ignition cable having a metallic shield, means forming a cable entrance into said hood, grounding means attaching the end of said shield to said hood short of the end of the cable, insert means fitting in said socket for connecting said cable to said terminal member, and an elastic sheath resiliently gripping said means, said sheath

having a sleeve portion adapted to engage the outside of said terminal member to hold said connecting means attached thereto and enclose and seal said socket, and said sheath being spaced from said cable entrance and loosely supported on said end of the cable.

5. A harness for connection to a high voltage component having a cylindrical casing and a tubular socket terminal member, comprising a tubular metallic hood adapted to telescope over the casing and shield said terminal, an ignition cable having a metallic shield, means forming a cable entrance into said hood, grounding means attaching the end of said shield to said hood short of the end of the cable, insert means fitting in said socket for connecting said cable to said terminal member, and an elastic sheath resiliently gripping said means, said sheath having a sleeve portion adapted to engage the outside of said terminal member to hold said insert means attached thereto and enclose and seal said socket, said sheath being spaced from said cable entrance and loosely supported on said end of the cable, said hood including a detachable closure at the other end of the hood, and means interengaging said closure and hood externally of the hood to afford unimpeded access to said terminal and cable when the hood is attached to the casing.

6. A harness for connection to a high voltage component having a cylindrical casing and a tubular socket terminal member, comprising a tubular metallic hood having at one end a mouth portion adapted slidably to telescope over and electrically contact said casing so that said hood encloses said terminal and said hood and casing entirely shielding said component, an ignition cable having a metallic shield, means forming a cable entrance into said hood including grounding means for connecting the cable shield to said hood, insert means fitting in said socket for connecting said cable to said terminal member, and an elastic sheath resiliently gripping said means, said sheath having a sleeve portion adapted to engage the outside of said terminal member to hold said insert means attached thereto and enclose and seal said socket, said sheath being spaced from said cable entrance and loosely supported on said end of the cable, said hood including a detachable closure at the other end of the hood, and means interengaging said closure and hood externally of the hood to afford unimpeded access to said terminal and cable when the hood is attached to the casing.

7. A harness for connection to a high voltage component having a cylindrical casing and a tubular socket terminal member, comprising a tubular metallic hood having at one end a mouth portion adapted slidably to telescope over and electrically contact said casing so that said hood encloses said terminal and said hood and casing entirely shield said component, an ignition cable having a metallic shield, means forming a cable entrance into said hood including grounding means for connecting the cable shield to said hood, means for connecting said cable to said terminal socket member including a cylindrical insert plug fitting in said socket and a clip for attachment to said cable, said clip being formed to telescope over and grip said plug and an elastic sheath resiliently gripping said connecting means, said sheath having a sleeve portion adapted to engage the outside of said terminal member to hold said connecting means attached thereto and enclose and seal said socket, said sheath being spaced from said cable entrance and loosely supported on said end of the cable, said hood including a detachable closure at the other end of the hood, and means interengaging said closure and hood externally of the hood to afford unimpeded access to said terminal and cable when the hood is attached to the casing.

8. For shielding an ignition coil having a cylindrical metal casing and a plurality of spaced terminals including a tubular socket terminal member, a connector comprising a tubular metallic hood having a mouth portion slidably fitting over said casing, a plurality of cable en-

trance forming means on said hood for receiving cables for connection to said terminals respectively, said mouth portion adjustably fitting said casing so that said openings may be positioned in proper relation to said terminals, a removable insert plug fitting in said socket member, a clip formed to telescope over and grip said insert, and an elastic sheath resiliently gripping said clip, said sheath having a sleeve portion adapted to engage the outside of said tubular socket member to hold said insert plug and clip attached thereto.
